United States Patent Office.

HORATIO N. TAFT, OF SAG HARBOR, NEW YORK.

Letters Patent No. 64,808, dated May 14, 1867.

IMPROVED DOOR-FASTENER.

The Schedule referred to in these Letters Patent and making part of the same.

TO ALL WHOM IT MAY CONCERN:

Be it known that I, HORATIO N. TAFT, of the town of Sag Harbor, in the county of Suffolk, and State of New York, have invented a new and useful Portable Combination Door-Fastener; and I do declare that the following is a full, clear, and exact description thereof, which will enable those skilled in the art to make and use the same, reference being had to the accompanying drawings, which form a part of this specification, and to the letters of reference marked thereon, in which—

Figure 1 represents a side view of the parts of the door-fastener put together.

Figure 2 is an edge view.

Figure 3 represents it as when used and applied as a door-fastener.

Similar letters of reference indicate corresponding parts in the drawings.

My invention consists in so constructing a portable or pocket door-fastener that the parts of which it is composed shall both separately and in combination form articles, tools, or instruments of great convenience and utility.

My door-fastener is intended for fastening doors on the inside when the doors are destitute of locks or bolts, or when they are inoperative, and it is formed of two pieces, as represented in the drawing, marked A and B. A has a hook or bit at the end, which is forced into the casing or jamb of the door when it is applied as a fastener. There is a slot-hole through this piece at g, fig. 1, which, in applying it as represented in fig. 3, is left just outside of the casing and door. This slot is made of suitable size to admit the piece B with its edge against the door and casing, as represented. In this situation it acts as a stop or bar to all entrance from the outside, unless the force applied to the door is sufficient to tear the bit E from the casing. When the two pieces A and B are combined, as in figs. 1 and 2, they form tweezers, which are useful for various purposes. A is curved, so that the ends are thrown apart when the two are combined. The end of A, and a good portion of its length, is made thin and elastic, so that it readily springs under the pressure of the thumb when used as tweezers. There is another curve in A opposite the slot-hole, the pieces only being in actual contact at two places. B is a straight-sided piece, except that the extreme end is somewhat tapered to fit it for a small screw-driver. To use it as such it is put through the slot as seen in fig. 3, when A serves as a handle. F is a small stud, with a button or conical head. This head is passed through the slot at g, which at this end is made sufficiently large for that purpose. The other portion of the slot is narrow, so that the head laps over the slot on each side. When the button-head is inserted at g, and the end of the screw-driver is slipped up to the bit of A, the two are attached together as firmly as desired. The curve opposite the slot allows A to spring a little under the pressure of the button, thus creating sufficient friction to hold them in place. A screw may be used to hold the two together if desired.

I do not confine myself to the particular manner of construction of the door-fastener as before described. As before stated, the two pieces may be held together as tweezers by a screw instead of the button-headed stud, or by a clasp or a sleeve; and the two pieces may be hooked together when used as a door-fastener, so that the stud and slot might be altogether dispensed with. The needle may be attached to either of the pieces, and in any manner; but what I claim as new, and desire to secure by Letters Patent, is—

A combination portable door-fastener, constructed, combined, and operating substantially as herein shown and described.

H. N. TAFT.
